UNITED STATES PATENT OFFICE.

GEORGE C. BRUHN, JR., OF WHEELING, WEST VIRGINIA.

LIQUID-FUEL-DELIVERY DEVICE.

1,402,565.

Specification of Letters Patent.

Patented Jan. 3, 1922.

Application filed April 21, 1921. Serial No. 463,308.

To all whom it may concern:

Be it known that I, GEORGE C. BRUHN, Jr., a citizen of the United States of America, and resident of Wheeling, county of Ohio, 5 and State of West Virginia, have invented certain new and useful Improvements in Liquid-Fuel-Delivery Devices, of which the following is a specification.

This invention relates broadly to liquid- 10 fuel delivery devices, and more specifically to a reserve providing equipment for fuel supply reservoirs.

The primary object of the invention is to provide a fuel delivery device for the main 15 supply tanks of motor vehicles whereby is created in such tank a reserve supply of liquid fuel which may be drawn upon in cases of emergency.

More specifically stated, it is the object 20 of this invention to provide mechanism designed primarily for use in the main fuel-supply tanks or reservoirs of motor vehicles, which shall be operative for furnishing fuel until the supply in the tank has 25 fallen to a predetermined low level, which shall suspend operation at said level, and which is capable of manual adjustment following such suspension to render it operative for delivering the remainder, or reserve supply, of fuel contained in the tank.

In describing the invention in detail, reference is herein had to the accompanying drawings, in which—

Figure 1 is a side elevation of the invention applied to a fuel supply tank of either the suction-feed or force-feed type, said tank being shown in vertical section;

Figure 2 is an enlarged vertical section of the invention;

Figure 3 is an enlarged side elevation of the lower end portion of the invention;

Figure 4 is a side elevation of the upper end of the invention viewed from a point at right angles to the viewpoint in Figs. 45 1 and 2; and—

Figure 5 is a view similar to Fig. 1, showing the invention modified to adapt it for use in either a force-feed or a gravity-feed tank.

Referring to said drawings, 1 indicates a pipe-fitting of approximately T-coupling form, the same having its lower end exteriorly threaded, as shown at 2, for mounting in the top of a fuel supply tank 3, and being 55 formed with a laterally extending nipple 4 adapted to be coupled to a feed line leading

to a vacuum tank or auxiliary reservoir from which fuel is fed to the carburetor by gravity.

Depending within the tank 3 from the 60 lower threaded end of said fitting 1, and preferably brazed or soldered to the latter, is a pipe 6 which carries upon its lower end a short length of tubing 7 of relatively large diameter, said tubing being preferably 65 attached to said pipe by brazing. Slidably received within the lower end of said tubing 7 is a reduced end or nipple 8 formed on or carried by a second pipe 9 having a diameter approximating that of said tubing. Said 70 pipe 9 has its lower end disposed closely adjacent to the bottom of the tank, as shown in Fig. 1.

A rod 10 of small diameter and having a 75 supporting crosshead 11 on its upper end is directed downward through the fitting 1, a bore 20 being provided therefor in the upper end of the latter, and thence extends downward through the alined pipes and has its lower end projecting outward from the 80 pipe 9. Said rod constitutes a support for the vertically movable pipe 9, a spring 12 being interposed between a nut 13 threaded on the projecting end of said rod and the end of said pipe, or between said nut and an 85 internal shoulder 14 provided in said pipe, such shoulder, when the same is employed, being preferably constituted by a collar brazed within the pipe at a suitable point adjacent to the lower end of the latter. 90

A suitable packing gland or cap 5 is 95 threaded upon the upper end of the fitting 1 about the rod 10, as shown. Said rod is normally disposed with the crosshead 11 thereof seated directly upon said cap 5, as shown in Fig. 1 and as is indicated in dotted lines in Fig. 4. In such position of the rod a spiral spring 15 interposed between the lower end of the pipe 6 and the reduced end or nipple 8 of the pipe 9 is permitted to hold said pipe 9 depressed to the position shown in Figs. 1 and 3, in which ports 16 provided in said nipple are uncovered, permitting unobstructed entrance of liquid fuel to be supplied to the vacuum tank or auxiliary fuel 100 reservoir.

When the motor of the vehicle has stopped, due to exhaustion of the fuel in the tank to the level at which it will not enter the inlet ports 16, the reserve supply located below 110 said level may be rendered available by the mere act of elevating the rod 10 and mount-

ing the crosshead 11 thereof in seats 17 provided therefor in upright standards 18 of appropriate length carried by the cap 5. When the rod is so elevated, the pipe 9 is drawn upward against the tension of the spring 15 to a point where the lower end of the enlarged lower portion 7 seats firmly upon a washer 19 carried by said pipe in encircling relation to said nipple 8, forming a sealed joint between said pipes, whereupon the pressure or suction, as the case may be, acts to feed fuel upward through the lower end of the pipe 9; or, as is obvious, the washer 19 may be dispensed with by shaping the adjacent ends of the tubing 7 and pipe 9 to provide a ground joint.

The tension of the spring 12 is sufficient to maintain the rod 10 firmly seated both when in its lowered and elevated positions.

20 In the modified construction of the invention shown in Fig. 5, which is designed for use in tanks from which the fuel is furnished either by pressure or gravity, the fitting 1^a is mounted in the bottom of the tank 3^a and 25 the use of the pipe 6 and tubing section 7, shown in Figs. 1 and 2, is dispensed with. A short pipe 9^a has a reduced end or nipple 8^a telescoped within the inner end of said fitting and resting against the end of a spiral 30 spring 15^a which tends to hold said pipe thrust outwardly in a position in which ports 16^a provided in said nipple are uncovered, as shown. A rod 10^a is directed through said fitting 1^a and pipe 9^a and has a nut 13^a 35 threaded upon the projecting end thereof against one end of a spiral spring 12^a which has its opposite end resting against the adjacent end of the pipe 9^a.

40 In its normal operation, the rod 10^a is disposed with the crosshead 11^a thereof seated upon the standards 18^a carried by the cap 5^a for holding the pipe 9^a drawn downward against the tension of the spring 15^a to a position in which the ports 16^a are closed 45 against the passage of liquid fuel therethrough. When the fuel has been exhausted to a level at which it will not enter the upper end of the pipe 9^a, the rod 10^a is drawn outward and turned to a position in which 50 its crosshead 11^a is disposed between the standards 18^a, whereupon, actuated by the spring 12^a, it is drawn inward to a position in which its crosshead seats directly upon the cap 5^a, allowing the spring 15^a to thrust 55 the pipe 9^a to a position wherein the ports 16^a are open for the passage of fuel therethrough.

What is claimed is—

1. The combination with a liquid fuel 60 tank, of an outlet passageway comprising alined non-rotatable members disposed in telescopic relation, one of said members being stationary and the other movable, one of said members having inlet ports in the 65 telescoping portion thereof, said ports being

open at one elevation of said movable member and closed at another, tension means normally holding said movable member at the first mentioned elevation, and means for shifting said movable member to the second 70 mentioned elevation.

2. The combination with a liquid fuel 75 tank, of an outlet passageway comprising alined non-rotatable members disposed in telescopic relation, one of said members being stationary and the other movable, one of said members having inlet ports in the telescoping portion thereof, said ports being open at one elevation of said movable member and closed at another, tension means 80 adapted to normally hold said movable member at the open-port elevation, and a rod having connection with said movable member through the interior of said stationary member, said rod being adapted to 85 permit said movable member to occupy said open-port elevation and being shiftable for carrying said movable member to the other elevation against the force exerted by said tension means. 90

3. The combination with a liquid fuel 95 tank, of a pipe fitting seated in the top of said tank and adapted for connection with a motor supply line, a pipe depending from said fitting within the tank, a relatively shorter pipe in telescoping relation to the first mentioned pipe and having its lower end disposed adjacent to the bottom of the tank, one of said pipes having fuel inlets 100 in the telescoping portion thereof, yieldable means normally maintaining said shorter pipe depressed in a position wherein said inlets are uncovered, and a vertically movable support for said shorter pipe, said support being adapted for adjustment to elevate said shorter pipe to a position wherein said inlets are closed. 105

4. The combination with a liquid fuel 110 tank, of an outlet passageway comprising vertically alined pipes depending from the top of the tank, the upper of said pipes having its lower end located a spaced distance from the bottom of the tank, the lower pipe being shorter than the upper pipe and having its upper end in telescoping relation to 115 the lower end of the latter and having its lower end located adjacent to the bottom of the tank, one of said pipes having inlet ports in the telescoping end portion thereof, said ports being open in the lowered position of the lower pipe and closed in the elevated position of the latter, tension means normally holding said lower pipe in its lowered position, and a support for said lower pipe, said support being shiftable for moving said lower pipe to its elevated position. 120

5. The combination with a liquid fuel 125 tank, of an outlet passageway comprising vertically alined pipes depending from the top of the tank, the upper of said pipes hav- 130

ing its lower end located a spaced distance from the bottom of the tank, the lower pipe being shorter than said upper pipe and having its upper end in telescoping relation to the lower end of the latter and having its lower end located closely adjacent to the bottom of the tank, one of said pipes having inlet ports in the telescoping end portion thereof, said ports being open in the lowered position of the lower pipe and closed in the elevated position of the latter, tension means normally holding said lower pipe in its lowered position, and a rod extending vertically through said pipes into supporting relation to the lower pipe and shiftable vertically for elevating the latter to port closing position.

6. The combination with a liquid fuel tank, of an outlet passageway comprising vertically alined pipes depending within the tank, the upper of said pipes having its lower end located a spaced distance from the bottom of the tank, the lower pipe being

shorter than said upper pipe and having its upper end in telescoping relation to the lower end of the latter and having its lower end located closely adjacent to the bottom of the tank, one of said pipes having inlet ports in the telescoping end portion thereof, said ports being open in the lowered position of the lower pipe and closed in the elevated position of the latter, tension means normally holding said lower pipe in its lowered position, and a rod extending vertically through said pipes and having a nut threaded upon its lower end in supporting relation to the lower pipe, said rod being vertically movable for elevating said lower pipe to port closing position, and means for supporting said rod in its elevated position.

In testimony whereof, I affix my signature in presence of two subscribing witnesses.
